UNITED STATES PATENT OFFICE.

CHARLES ALBERT YALE, OF BURLINGTON, VERMONT, ASSIGNOR TO YALE WONDER CLOCK COMPANY, OF SAME PLACE.

DESIGN FOR A DIAL FOR COIN-CONTROLLED APPARATUS.

SPECIFICATION forming part of Design No. 34,205, dated March 12, 1901.

Application filed February 15, 1901. Serial No. 47,515. Term of patent 3½ years.

To all whom it may concern:

Be it known that I, CHARLES ALBERT YALE, a citizen of the United States, residing at Burlington, in the county of Chittenden and State of Vermont, have invented and produced a new and original Design for Dials for Coin-Controlled Apparatus; and I do declare the following to be a full, clear, and exact description of the same, reference being had to the accompanying drawing, forming a part thereof.

My invention relates to new and original designs in dials for coin-controlled apparatus.

The accompanying drawing illustrates a plan view of my new design.

As shown in the drawing, the design consists of a disk having a series of stars arranged in a semicircle near the upper portion of the dial and a series of stripes radially arranged at the lower portion of the disk. A border-line surrounds the stars and stripes, and a line separates them from the center of the dial. A rectangular panel is arranged

near the lower portion of the disk, and a spread-eagle is mounted upon the panel-frame and carries a ribbon banner in its mouth. The space within the panel and immediately above the eagle is plain and unornamented. A series of lines radiate from the outer border to the periphery of the disk.

The design is produced upon the dial in the national colors—red, white, and blue—and the distinguishing feature of the design is the arrangement of stars and stripes and the spread-eagle mounted upon the panel-frame.

Having thus described my new and original design, what I claim is—

The design for a dial for coin-controlled apparatus, substantially as shown and described.

In testimony whereof I affix my signature in the presence of two witnesses.

CHARLES ALBERT YALE.
